UNITED STATES PATENT OFFICE.

JACOB E. PETERSON AND JACOB M. PETERSON, OF DAYTON, OHIO.

ROTARY ENGINE.

No. 821,734.

Specification of Letters Patent.

Patented May 29, 1906.

Application filed February 26, 1906. Serial No. 302,840.

To all whom it may concern:

Be it known that we, JACOB E. PETERSON and JACOB M. PETERSON, citizens of the United States, residing at Dayton, in the county of Montgomery and State of Ohio, have invented certain new and useful Improvements in Rotary Engines; and we do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to new and useful improvements in rotary engines.

The objects of the invention are, first, to provide an engine of the above type with a high degree of efficiency, which is obtained by balancing the pressure equally on opposite sides of the revolving piston; secondly, to govern the action of the traveling vanes by positive means, and, thirdly, to admit the driving power to the piston simultaneously on opposite sides and at the same pressure.

Preceding a detail description of the invention reference is made to the accompanying drawings, of which—

Figure 1 is an end elevation of my improved rotary engine. Fig. 2 is a horizontal sectional view on the line *x x* of Fig. 1. Fig. 3 is a vertical sectional elevation on the line *y y* of Fig. 1.

In a detail description of the invention similar reference characters indicate corresponding parts.

1 designates the engine-casing, having oppositely-disposed inlet-ports 2 2 and exhaust-ports 3 3, through which steam or other source of power is admitted simultaneously at uniform pressure and is discharged through the oppositely-disposed exhaust-ports simultaneously. The engine-casing is a cylindrical shell having its ends terminated in in-turned flanges 1^b. The diameter of said cylinder at any point between the in-turned flanges is the same.

4 designates oppositely-disposed slides which are supported upon the top and bottom portions 1^a of the casing and are slidably connected with suitable operating-rods 5 5, pivotally connected to an operating-rod 6, which is pivoted at 7 to the side of the cas-

ing. The top and bottom portions 1^a of the cylinder form the inner inclosures of the ports and are of flattened form on their inner and outer surfaces in order to provide a suitable support for the slides on their outer sides and a suitable bearing for the elongated packing-strips 9, which extend the length of the piston and will be again referred to. The rod 6 is operated to oppositely shift the slides 4 to simultaneously uncover and cover the oppositely-disposed inlet-ports 2 and exhaust-ports 3. It will be seen that other means may be employed to simultaneously shift the slides 4, the means just described, consisting of the connecting-rods 5 5, and 6, being one means only. The top and bottom horizontal portions 1^a of the casing, it will be understood, join the casing at their ends.

The inner sides of the parts 1^a of the casing are flattened, as before stated, and have dovetail recesses to receive suitable strips of packing 9, which project a proper distance on the interior of the casing to provide proper packing to prevent back pressure upon the vanes. The packing-strips 9 present throughout their exposed sides a flat surface in order to conform to the uniformly-cylindrical surface of the piston. The said piston 10 is of hollow form, with a hub 11, which is mounted upon shaft 12, having bearings 13. The piston is of uniform diameter with the exception of the extreme ends, which terminate in annularly outwardly extended radial portions 10^a. The outer periphery of these parts 10^a of the piston meet the inturned flanges 1^b of the casing and provide a proper place for external packing between each end of the piston and the casing. Extending between the hub and the rim of the piston are a series of four webs 14, each of which has a continuous opening of two diameters—to wit, 15 15 and 16—the former extending throughout the length of the piston.

Within the larger openings or spaces 15 there is a series of four vanes 17, united at their inner edges to a series of guide-pins 18, that extend into the smaller openings 16. The vanes 17 are controlled throughout the rotation of the piston by rollers 20, which run in cam-races 19, to be presently again referred to. The steam or other source of power entering the inlet-ports 2 2 under uniform pressure rotate the piston by engaging the opposite vanes 17, and the steam or other

source of power expands on opposite sides of the piston in an even-balanced pressure. The vanes 17 are held outwardly against the interior of the casing by the rollers 20 and 5 the cam-races 19, and as said vanes reach the exhaust-ports 3 they are drawn inwardly toward the axis of the piston by the rollers 20 entering the upper and lower flattened portions of the cam-races 19. The rollers 20 are 10 mounted at the ends of the vanes 17 by any suitable connection. The present connections consist of a series of angular levers 21. One end of each of said levers extends on the exterior of the piston and supports a roller 15 20, while the other end is secured directly to the vanes 17. These rollers 20, as before stated, travel in the races 19, said races being flattened above and below to a suitable extent to move the vanes entirely within the 20 piston when said vanes assume a vertical position. The upper and lower portions of said cam-races begin to move the vanes inwardly when said vanes arrive in proximity to the oppositely-disposed exhaust-ports 3. The 25 cam-races 19 on each side of the casing coincide with the contour of said casing, so that the vanes are held in contact with the interior of the piston-chamber during the period of expansion. The vanes when contracted 30 to their limit pass snugly by the packing-glands 9 and are in position to make contact with the packing-glands 9 when the cylinder is exhausting. There is thus a substantially impassable connection for a time between 35 the vertical piston-vanes and the packing, which prevents any appreciable back pressure on the piston. The cam-races 19 are formed in a ring 22, secured to the ends of the casing.

40 The rings 22 occupy positions at the extreme ends of the casing, so that the air is at all times enabled to maintain contact with the rollers and the cam grooves or races, thereby preventing a detrimental increase of 45 temperature due to friction between these parts. These end rings 22 constitute open heads at each end of the cylindrical casing, and their inner peripheries need only be of suitable depth to provide the proper width 50 for the races 19. Between the outer sides of the inturned flanges 1^b of the casing and the rings 22 there is provided space 1^c for suitable packing, hereinbefore referred to, in connection with the inturned flanges 1^b and 55 the piston extensions 10^a.

Having described our invention, we claim—

1. In a reversible rotary engine, a cylindrical casing having its ends terminated in inturned flanges, said casing having oppositely-disposed flat portions with oppositely-disposed inlet and outlet ports lying between said flattened portions and the adjacent sides of said casing, rings having cam-races on their inner sides and united to the 65 ends of the cylindrical casing beyond the inturned end flanges of said casing, a rotating piston having its ends terminated in outwardly and annularly extending flanges which meet the inturned flanges of the casing, 70 the diameter of the piston being uniform between said end flanges, a series of vanes mounted within the piston, roller connections between the ends of said vanes and the cam-rings on the ends of the cylindrical casing, 75 and packing-strips placed at opposite points in the flattened portions of the casing, said packing-strips presenting to the piston-vanes a straight surface throughout the lengths of said piston-vanes, and slides controlling the 80 oppositely-disposed inlet and outlet ports.

2. In a reversible rotary engine, a cylindrical casing having oppositely-disposed inlet and outlet ports, the ends of said casing terminating in inturned flanges, a rotating piston 85 having its ends terminated in outwardly-extending annular flanges which meet the inturned flanges at the ends of the casing, rings united to the ends of the casing and providing suitable annular packing-pockets on the exterior of the ends of the casing and the piston, 90 said rings having cam-races which lie inwardly from a circle at opposite points, piston-vanes mounted in the periphery of the piston between the end flanges of said piston 95 and the end flanges of the casing, arms supporting rollers extending from the ends of the piston-vanes, said rollers lying in the cam-races in the rings attached to the ends of the casing, and packing-strips united to 100 the upper and lower flattened sides of the casing and presenting to the moving vanes a uniform surface, substantially as specified.

In testimony whereof we affix our signatures in presence of two witnesses.

JACOB E. PETERSON.
